SOLVENT AND PROCESS FOR DEWAXING
MINERAL OILS

Donald S. McKittrick, Oakland, and Hilary J. Henriques, Berkeley, Calif., assignors to Shell Development Company, San Francisco, Calif., a corporation of Delaware

No Drawing. Application June 20, 1936,
Serial No. 86,356

10 Claims. (Cl. 196—18)

This invention relates to a process for separating various waxy substances from mineral oil containing the same. More particularly, it pertains to an improved diluent for decreasing the viscosity of the oil and the solubility of the wax, while improving the solubility of the oil in the liquid phase produced when solid wax is separated from oil, whereby the wax and the oil are separated more readily than has been possible heretofore.

Mineral oils naturally contain varying amounts of waxy hydrocarbons, often designated as paraffin wax or petrolatum, and hereinafter generically designated as waxes, which at normal or elevated temperatures are dissolved in the liquid hydrocarbons, hereinafter referred to as oil, but which solidify or become extremely viscous at lower temperatures. If these oils are to be used as lubricants at these reduced temperatures the solidified or highly viscous wax causes the oil to resist flow. When the wax content is too low to impede flow, it may, nevertheless, cause cloudiness in the oil. It becomes necessary, therefore, to effect the removal of all or some of the wax.

The first step in such a process is the creation of conditions under which the wax has a minimum solubility in the phase containing the oil. This wax probably contains aliphatic hydrocarbons and/or naphthenic and other hydrocarbons; it belongs to the group of components of petroleum which are the least soluble in selective solvents. The removal of wax may be accomplished by any of several methods.

In accordance with one of these methods, the oil is chilled to a temperature substantially below that at which the wax solidifies and the wax is separated from the liquid oil by mechanical means. As an improvement in such a process, it is common to add a non-selective diluent, such as liquefied, normally gaseous hydrocarbons, light naphthas, etc., to the oil to reduce its viscosity and facilitate the mechanical separation.

In another method, a selective solvent medium is added to the initial oil, and the wax-free components of the initial oil are dissolved therein. This method necessitates the use of a solvent medium which is sufficiently selective to dissolve the oil at a suitable dewaxing temperature without dissolving the wax. The ordinary selective solvents which are employed for example in liquid-liquid solvent extraction processes to dissolve certain types of oils which are less paraffinic in nature from those which are more paraffinic in nature are not in general suitable for use as solvent media, because in dewaxing processes the

solvent is used to dissolve the desired oil which, in the case of extraction processes, it is desired to recover in the liquid phase insoluble in the solvent.

Certain of such selective solvents may, however, be employed for dewaxing purposes by adding thereto a quantity of a secondary solvent, sometimes referred to as a solubility enhancing solvent. The addition of the secondary solvent improves the miscibility of oil and selective solvent, but in most cases destroys the selectivity of the resulting mixture between wax and oil, so that the resulting mixture of primary selective solvent and solubility enhancing solvent is to a great extent equivalent to a non-selective diluent, and functions only to reduce the viscosity of the chilled oil.

We have discovered that mixtures of a propyl alcohol with dihalogenated aliphatic hydrocarbons having between one and four carbon atoms, particularly 1,2 dichloro ethane (ethylene dichloride) and 1,2,dichlor propane (propylene dichloride), are particularly suitable for use as dewaxing solvents. Other halogenated hydrocarbons, such as 1,2, dichloro ethene (dichlor ethylene), and 1,1, dibromo ethane (ethylidine bromide) may also be employed, but we prefer the above named chlorinated compounds. Isopropyl alcohol is superior to normal propyl alcohol, and shows a high selectivity between wax and oil when diluted with these dihalogenated hydrocarbons and makes it possible to obtain unusually high yields of dewaxed oil of moderately low pour points.

Suitable solvent mixture may, for example, consist of from 15 to 90% isopropyl alcohol and from 10 to 85% of a di-halogenated hydrocarbon, such as 1,2, dichloro ethane.

The method which is subject to our invention relies primarily on the peculiar properties of the above mixtures of solvents, which were found to create a condition in which there is a large difference between the solubility of the solid or waxy components of the initial oil and the solubility of the liquid or oil components thereof. In one aspect, our method comprises the steps of mixing a waxy oil, such as lubricating oil, fuel oil, etc., which may be either a residual or a distillate oil, with our selective solvent and solubility enhancing solvent, and chilling the resulting mixture to a dewaxing temperature to solidify the wax, which may then be separated from the liquid portion of the system by any mechanical means, such as filtration, cold settling, or centrifuging, depending upon the character of the wax. Our process is, however, particularly suit-

able for filtration methods. The dewaxing temperature may, for example, be slightly below the melting point of the lowest melting wax which it is desired to remove. The pour point of the dewaxed oil may in certain cases be slightly higher than the dewaxing temperature, but by adjusting the proportions of selective solvent and solubility enhancing solvent, as described below, pour points which are as much as 20° F. below the dewaxing temperature may be obtained.

It is desirable, although not essential, to produce a homogeneous wax-oil-solvent system prior to the precipitation step. To achieve this, the temperature of the system may initially be raised to somewhat above the dewaxing temperature. We have, moreover, found that excellent filtration rates are obtained by heating the oil-solvent mixture to a temperature within the range from 65° C. to 100° C. or higher, and then cooling it slowly to the dewaxing temperature. When the mixture is initially warmed, it is necessary to cool the oil-solvent mixture, and this may be effected by indirect cooling or self-refrigeration. Where very low pour points are not essential, our solvent mixtures may often be mixed with the oil at ordinary temperatures of the order of 18° C., thereby obviating the necessity of chilling the oil.

The chilling, when used, is not only for the purpose of merely freezing out the wax, as in the processes now practiced, but also for the purpose of increasing the selectivity of the solvent mixture which may have been added to the oil at a temperature at which it is less selective. This feature distinguishes our process from those in which the wax is caused to separate by mere chilling, and a non-selective solvent or diluent is added to reduce the viscosity of the oil and to expedite the separation of the solidified wax. In this connection it should be noted that the above selective solvents become more selective at lower temperatures.

Under certain conditions the wax which is precipitated according to the procedure outlined above, either with or without chilling during precipitation, may be so soft as to make its separation difficult. It is in these cases advantageous to chill the precipitated wax during or just prior to its final removal to harden it. Subsequently the solvent mixture is removed from the separated liquid by any means, such as distillation.

To be filterable or otherwise separable from the oil-solvent phase, the wax particles must be of suitable form, size and strength and/or hardness. We have found that if in precipitating the wax a very small amount of liquid oil is separated out from the oil with the wax crystals, clusters of crystals are formed and the separation of wax from the solution of oil and solvent is facilitated. The amount of oil necessary for this purpose depends upon the size of the initial wax crystals, which, in turn, depends among other things, upon the nature of the wax and the rate of chilling. In processes in which the crystals are extremely small and the wax content of the initial oil is high, as much as 1.0% of the main body of the oil may be desirable. In other cases, as when the crystals are larger, and/or when less wax is present, lesser amounts of oil may be desirable, and it is frequently practical to permit substantially no oil to be separated out with the wax. Since the separation of an excess quantity of oil reduces the yield of dewaxed oil, it is desirable to control the amount of the oil which is separated with the wax, as described below.

A convenient method of controlling this amount of oil is to regulate the concentration of the halogenated hydrocarbon gas in the solvent mixture. The necessary dilution ratio, i. e., the ratio of the combined solvent mixture to the initial oil, is generally determined by the viscosity of the oil and the solvent mixture and by the selectivity of the solvent mixture at the dewaxing temperature, and is made as low as possible with a view of conserving the solvent. When using the new solvent mixtures of our invention, the dilution ratio may be much lower than the ratio employed with the known solvent mixtures. For example, we have obtained excellent results when using a dilution ratio of 2:1, and even lower ratios, such as 1:1 may be employed, although we prefer to employ ratios of about 4:1. At very low temperatures ratios as high as 8:1 may be desirable.

For a given dilution ratio, the greater the concentration of the propyl alcohol, in the dewaxing mixture, the more complete will be the precipitation of wax, and extremely low pour points may often be obtained. However, since the alcohol has a relatively low solvent power for the oil, the oil-solvent system will in this case form two liquid phases, in addition to the solid wax phase, and the yield of the dewaxed oil will be extremely low. When a high concentration of halogenated hydrocarbons is employed, the oil-solvent system may exist as a homogeneous liquid phase, and both pour points and yields of dewaxed oil will be increased, although the use of an excess of halogenated hydrocarbons may again cause the formation of two liquid phases. There is, therefore, at least one, and sometimes two compositions of the combined solvent mixture forming a transition point between the liquid-solid and liquid-liquid-solid phase systems. The transition composition will, of course, depend upon several factors such as the dilution ratio, the dewaxing temperature, the specific solvents employed, and the character of the oil, but may be easily determined empirically for any given situation.

We have found that when the volume concentration of the halogenated hydrocarbons in the mixed dewaxing solvent is lower than about 10% below the concentration corresponding to the transition composition, the yields of dewaxed oil are reduced quite out of proportion to the improvement in the pour point. Moreover, we have found that the most efficient dewaxing operations are those which are carried out by employing dewaxing solvent mixtures having compositions near the transition composition, i. e., in which the concentration of the halogenated hydrocarbons fall in the range from 10% below to 20% above the transition concentration. Using greater quantities of solubility enhancing agent results in greater yields, but the pour points of the dewaxed oil will often be undesirably high. A reference to a transition point is, in the present paragraph and in the claims, intended to refer to that transition composition which contains the higher concentration of alcohol, in situations in which the system has several transition points.

Such solvent mixtures as are used in accordance with the present invention may, for example, at temperatures of about 0° F. to -10° F., have complete or substantially complete solubility for oil having specific gravities d_{15}^{15} between 0.90 and 0.94 and refractive indices n_D^{20} between 1.50 and 1.52, and substantially no solvent power for wax which is solid at the said temperatures, i. e., not more than a few tenths of one per cent of wax

will be dissolved at these temperatures; such an oil may, for example, have a viscosity of between 50 and 55 sec. Say. Univ. at 210° F. Mixtures of solvents having this characteristic may, of course, be used also with oils of different refractive indices, specific gravities or viscosities.

The dewaxing process may also be carried out in several steps, the composition of the solvent mixture being regulated, and the process being carried out as described in the U. S. Patent No. 2,126,493.

The yields of dewaxed oil of a given pour point and the filtration rates can often be further increased by adding a small amount, generally between 0.2% and 1% of a pour point reducing substance, such as tetrastearyl glucose, pentaerithritetetrastearate distearyl picene, cracked residues, metallic soaps, etc., to the oil, preferably prior to chilling. Most of the pour point reducer separates from the oil with the wax and is not normally effective to lower the pour point of the filtrate, but is effective in the formation of filterable wax crystals.

The following example illustrates the superior results obtainable with our improved solvent mixtures. For comparison, the same oil was dewaxed without mixtures and with acetone-benzol mixtures, the latter mixture being commonly regarded as standard for dewaxing mineral oils.

Example.—Several samples of a Ventura distillate having a pour point of 95° F. were each diluted with four volumes of various solvent mixtures, heated to about 100° C., gradually cooled, and filtered at between -20° and -19° C. The compositions of the solvent mixtures and the yields are given as percent by volume. The results are shown in the table:

Expt. No.	Diluent		Yield of dewaxed oil	Final pour point of oil
	First solvent	Second solvent		
45	Isopropyl alcohol	1, 2, dichloro ethane		
1	Percent	Percent	Percent	° F.
2	32	20	84	-7.5
3	60	40	83	-7.5
4	20	20	84	-12.5
5	20	10	74	-12.5
6	35	5	85	-15
50	Acetone	Benzol ^a		
55	Percent	Percent		
6	35	65	91	+15
7	45	55	80	+10
8	55	50	80	+5
9	60	40	87	+0
10	70	20	85	0
11	75	25	83	+5

^a Contained 10 percent toluene.

It will be noted that our dewaxing mixtures may be used over a wide range of compositions, and that throughout the range the pour points of the dewaxed oil are materially lower than the pour points obtained with acetone-benzol mixtures. The lowest pour point obtainable with the latter dewaxing mixture when dewaxing at -20° C. was 0° F.

With a dilution ration of 1:4 at -20° C., the following compositions of solvent dewaxing mixtures corresponded to the transition point between one and two liquid phase systems: 83% isopropyl alcohol, 17% 1, 2, dichloro ethane; 55% acetone; 45% benzol. (A second transition point

occurs at the composition 24% isopropyl alcohol, 76% 1, 2, dichloro ethane, two liquid phases being formed when less than 24% isopropyl alcohol is in the solvent mixture, but, as is apparent from the above figures, the best results are obtained when operating in the vicinity of the transition point corresponding to an 83% alcohol concentration.)

The above example is presented only for the purpose of illustrating the efficiency of our new solvents, and to show the manner in which the pour point and yield may be varied by varying the relative concentrations of alcohol and halogenated hydrocarbon. Our invention is in no way limited to the specific mode of operation described in this example, since it is possible to employ other specific halogenated hydrocarbons, or other oil-solvent ratios.

We claim as our invention:

1. A selective solvent dewaxing mixture for petroleum oils, consisting of between 15 and 90% isopropyl alcohol and between 10 and 85% of a dichlorinated aliphatic hydrocarbon having two carbon atoms.

2. The dewaxing mixture according to claim 1 in which the chlorinated hydrocarbon is 1, 2, dichloro ethane.

3. The dewaxing mixture according to claim 1 in which the chlorinated hydrocarbon is 1, 2, dichloro ethene.

4. In the process of manufacturing low pour point lubricating oil from wax-bearing mineral oil substantially as described, the step of treating the oil with a solvent mixture to separate solid wax from the oil, said solvent mixture comprising a propyl alcohol and a di-halogenated aliphatic hydrocarbon having two carbon atoms, at temperatures sufficiently low to solidify the wax.

5. The process according to claim 4 in which the halogenated hydrocarbon is 1, 2, dichloro ethane.

6. The process according to claim 4 in which the alcohol is isopropyl alcohol.

7. The process according to claim 4 in which the wax is separated from the oil-solvent mixture by filtration.

8. The process of dewaxing mineral oils which comprises mixing said oil with a propyl alcohol, precipitating solid wax from the resulting oil-alcohol mixture in the presence of a di-halogenated aliphatic hydrocarbon having two carbon atoms, in such proportions that, at the temperature at which the wax is removed, the resulting mixture has substantially complete solvent power for the oil and substantially no solvent action on the wax, and mechanically removing the precipitated wax from the oil-solvent mixture.

9. The process according to claim 8 in which the concentration of the halogenated hydrocarbon is not smaller than 10% below the quantity necessary to prevent the formation of two liquid phases at the temperature at which the wax is removed from the oil-solvent mixture.

10. The process for dewaxing mineral oils which comprises mixing the oil with at least an equal volume of a solvent mixture containing between 15 and 90% isopropyl alcohol and between 10 and 85% of 1, 2, dichloro ethane, chilling the resulting oil-solvent mixture to precipitate the wax, and removing the precipitated wax from the oil-solvent mixture by mechanical means.
